Des. 232,366

Patented Aug. 13, 1974

232,366

CHRISTMAS ORNAMENT

Richard F. Goonen, 107 Washington St.,
Lafayette, Ind. 47905

Filed Apr. 30, 1973, Ser. No. 355,934

Term of patent 14 years

Int. Cl. D11—02

U.S. Cl. D29—1 B

FIG. 1 is a front elevational view of a Christmas ornament showing my new design;

FIG. 2 is a side elevational view of the Christmas ornament, the opposite side elevational view being substantially similar; and

FIG. 3 is a vertical sectional view through the Christmas ornament taken on the plane represented by the line 3—3 in FIG. 1.

I claim:

The ornamental design for a Christmas ornament, substantially as shown and described.
